(57) **CLAIM**

The ornamental design for a playing card, substantially as shown and described.

DESCRIPTION

FIG. 1 is a front, right side and top perspective view of a playing card comprising a new, original and ornamental design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines depict environmental subject matter only and form no part of the claimed design.
